UNITED STATES PATENT OFFICE

THOMAS F. DOWNEY AND JAMES DONALD, OF CHICAGO, ILLINOIS

STEAM-GENERATING FURNACE

Application filed May 5, 1928. Serial No. 275,495.

One of the objects of this invention is to provide an improved gravity feed furnace of the type which is adapted to be installed in front of a boiler.

5 Another object of the invention is to provide a tile-protected water-wall of such construction that damaged tiles may be readily replaced.

Another object is to provide a gravity-
10 feed furnace with a top water-wall of new and improved construction.

In the accompanying drawings,

Figure 1 is a transverse vertical sectional view taken approximately in the line of 1—1
15 of Fig. 5.

Fig. 2 is a section on line 2—2 of Fig. 1.
Fig. 3 is a front elevation of the furnace.

Fig. 4 is a section on line 4—4 of Fig. 1.
Fig. 5 is a section on line 5—5 of Fig. 1.

20 Fig. 6 is a perspective view of one of the elements comprised in the coal-feeding pockets.

Fig. 7 is a perspective view of one of the furnace-arch tiles.

25 Fig. 8 is a sectional view illustrating an alternative construction of the grates.

Although a furnace embodying the features of our invention may be used in connection with various types of boilers, we have
30 herein shown it as associated with a Scotch boiler 1, the main flue of which is indicated at 2, and some of the fire tubes at 2^a.

The furnace is located in front of the boiler and in communication with the flue 2. The furnace is herein shown as comprising a front wall 3 and side walls 4 formed of steel plates. In the front wall is a fire door 3^a and ash-pit doors 3^b. The furnace arch or water-wall comprises two parallel headers 5 each secured
35 to one of the side walls 4 and extending longitudinally of said walls, together with a series of spaced parallel tubes 6 extending transversely across the furnace and connected at their ends to the headers 5. In
40 the outer sides of the headers are clean-out openings 6^a aligned with the tubes 6.

Means is provided for supplying coal to the grate through the spaces between the tubes 6 adjacent to the headers 5. These spaces may be termed feed pockets. They

extend the full length of the grate on both sides of the furnace. In order to protect the tubes 6 from abrasion, we provide a series of castings 7 (Fig. 6), each consisting of a shield 8 of approximately semi-cylindrical form to fit upon one of the tubes 6, and flanges 9 on one end of the shield. The flanges 9 form a continuous series extending parallel with the adjacent header 5. The space between the two series of flanges 9 is covered by a steel plate 10. Between said two series of flanges 9 the tubes 6 are protected by means of tiles 11 which are supported by and surround said tubes.

As shown in Fig. 5, the length of each tile 11 measured longitudinally of the furnace is one-half the distance between the centers of two adjacent tubes 6. Each tile has in one side a recess 12 to accommodate a tube 6. The tiles are installed initially before the castings 7 are put in place, the tiles being slid toward the center line of the furnace from the spaces adjacent to the headers 5. After the tiles are in place, the castings 7 are set upon the tubes. When a tile requires replacement, the casting 7 which is in line with the damaged tile is removed, and the replacement made through the space normally occupied by said casting.

One of the headers 5 is connected to the lower portion of the boiler 1 by means of a tube 13, while the other header 5 is connected to the upper portion of the boiler by means of a tube 14.

Attached to each of the headers 5 is an upwardly inclined plate 15. In use, a supply of coal is piled between the plates 10 and 15, directly over the spaces between the shields 8.

The arrangement of grates, as shown in the present instance, includes a flat bottom grate 16 formed of shaking and dumping grate bars of any preferred construction, and two inclined side grates 17 of any preferred type, as, for example, the standard two-bar stationary type.

Means is provided for feeding coal from the feed pockets to the inclined grates and the bottom grate. In the construction shown in Fig. 1, said feeding means includes pusher

members 18 which occupy the space between the upper ends of the side grates 17 and the headers 5. Each pusher member is in the form of a rectangular casting which 5 may have air openings 19 therethrough, as shown in Fig. 5. The pusher members 18 are fixed upon a shaft 20 which is supported in bearings at the upper end of the adjacent inclined side grate. When in normal or idle 10 position the pusher members 18 are approximately in the same plane as the adjacent side grate, and support a quantity of coal extending up through the spaces between the shields 8.

15 Upon the outer or lower side of each pusher member is a cut-off flange 21 which is curved upon the axis of the pusher member. The curved cut-off flanges 21 form a substantially continuous series, as shown in Fig. 2, so that 20 when the pusher members are swung in the direction to force coal onto the bottom grate, the cut-off flanges close the feed pockets and thus serve to prevent coal from falling behind the pusher members.

25 The means herein shown for oscillating the pusher members 18 comprises a rock shaft 22 journaled in bearings on the side wall of the furnace and connected to several of the cut-off flanges 21 by means of crank arms 23 and links 24. On the forward outer end 30 of the shaft 22 is a hand lever 25 (Fig. 3) by means of which the shaft may be rocked to oscillate the pusher members. While hand levers have been herein shown for operating 35 the pusher members, it will be understood that power-actuated means might be employed for that purpose.

Means is provided for supplying heated air to support combustion. An air pipe 26 40 extends longitudinally of the furnace and above the middle of the tubes 6. Connected with said air pipe are transverse pipes 27 which extend above the spaces between the tubes 6. Extending downwardly from each 45 of the tubes 27 are tubes 28 which project into recesses 29 formed between adjacent tiles, said spaces extending to the lower sides of the tiles so as to allow air to be discharged directly over the fire. In the present construction, the recesses 29 are formed by 50 chamfering the corners of the tiles. Inasmuch as the pipes 26, 27 and 28 are above the arch, they are effectively protected from the fire. The front end of the pipe 26 is connected by means of a tube 30 to a suitable 55 source of supply (not shown) of air under pressure. If desired, the tube 30 may be connected to a steam pipe, so that steam may be sprayed over the fire.

60 In Fig. 8 we have shown an alternative construction of stoker grate. Only the right-hand half of the grate structure is illustrated. This alternative construction comprises a center dump grate comprising grate 65 bars 31 pivoted at 32 to swing downwardly

to dump the ashes. The means for operating the grate bars 31 comprises a shaft 33 having thereon a suitable number of crank arms 34 and links 35. At each side of the center dump grate is an inclined set of grate bars comprising, in this instance, two longitudinal series of stationary grate bars 36 and 37 and two series of pusher members 38 and 39 similar to the members 18 hereinbefore described. Normally, the grate bars 36 and 37 and the pusher members 38 and 39 lie in the same inclined plane.

The means for operating the upper series of pusher members 38 is generally similar to that shown in Figs. 1 and 2, and comprises 80 a shaft 40 which is connected to the pusher members 38 through the medium of crank arms 41 and links 42. Similarly, the series of pusher members 39 are operated by means of a shaft 43, crank arms 44 and links 45.

85 The shafts 40 and 43 are arranged to be simultaneously rocked by means of crank arms 46 and 47, respectively, which are connected to crank arms 48 and 49 on a shaft 50 by means of connecting rods 51 and 52. The 90 shaft 50 may be rotated by any suitable means, as, for example, worm gearing 53 connecting said shaft to a transverse shaft 54.

In operation, coal is fed as required to the 95 grates by means of the pivoted pusher members. The heated air supplied above the fire insures proper combustion, the hot gases entering the main flue 2 of the boiler and thence circulating through the fire tubes 2^a. The 100 heat within the furnace sets up a flow of water from the lower portion of the boiler through the tubes 6 to the upper portion of the boiler, thus securing approximate uniformity of water temperature in the boiler and thereby correcting a well-known disadvantage of the Scotch type of boiler.

105 If desired, the fuel feed openings may be closed in any preferred way, and the furnace operated by means of an oil burner. When oil is to be burned, the grates are removed, 110 and the side walls 4 protected by brickwork.

Various changes may be made in the construction and relative arrangement of the parts herein shown. For example, the form 115 of bottom grate shown in Fig. 8 may be used in connection with the form of side grates shown in Fig. 1.

We claim as our invention:

1. A steam-generating furnace comprising 120 a grate, and a tile-protected water-wall over the grate comprising a series of spaced parallel water tubes extending transversely of the furnace, a header at each side of the furnace connected to said tubes, there being fuel feed openings between said tubes adjacent to 125 said headers, a series of members for each of said series of fuel feed openings, each of said members comprising a semi-cylindrical shield for one of said tubes and flanges at one end of the shield, said flanges forming a sub- 130

stantially continuous series adjacent to and parallel with one of said headers, and tiles enclosing that portion of each tube which extends between the said series of flanges.

5 2. A furnace comprising a grate, and a tile-protected water-wall over the grate comprising a series of spaced parallel water tubes extending transversely of the furnace, a header at one side of the furnace connected to one end of each tube, means connecting the opposite ends of the tubes, there being fuel feed openings between said tubes adjacent to said header, a semi-cylindrical shield for that portion of each of said tubes which is adjacent to said header, and means projecting laterally from one end of each shield, said last-mentioned means forming a substantially continuous series adjacent to and parallel with said header whereby to define one side of 20 said fuel feed openings.

3. A steam-generating furnace comprising a grate, and a tile-protected water-wall over the grate comprising a series of spaced parallel water tubes extending transversely of the furnace, a header at each side of the furnace connected to said tubes, there being fuel feed openings between said tubes forming a series of openings adjacent to said headers through which coal may be fed, and means enclosing the upper part of that portion of each tube which extends between the adjacent feed openings and serving to protect said tubes from wear by the coal passing through said openings.

35 4. A furnace comprising a grate, a tile-protected water-wall over the grate having fuel openings formed at the sides thereof, means extending along the top of said water-wall for supplying heated air, nozzles extending downwardly from said means through said water-wall, a plate extending over said means from the openings on one side of said wall to the openings on the other side thereof, and inclined plates extending longitudinally of the furnace along the outer edges of said openings so that fuel may be piled on said plate to be fed through said openings into the furnace.

50 5. A steam-generating furnace comprising a grate, and a water-wall over the grate comprising a series of spaced parallel water tubes extending transversely of the furnace, a header at each side of the furnace connected to said tubes, there being fuel feed openings in said wall between said tubes forming a series of feed openings adjacent to said headers through which fuel may be fed, a shield of semi-circular cross section positioned over the top of each tube at each end adjacent to the headers to protect said tubes from wear by the fuel passing through said openings, and two rows of tiles between each adjacent pair of tubes abutting at their sides and ends and enclosing that portion of each

tube which extends between the two shields, each tile having a longitudinally extending recess in the side thereof embracing the side, top and bottom of the adjacent tube to protect the same, the shield at each end of each tube serving to cover a greater length of tube than any one of said tiles whereby to permit individual endwise withdrawal of said tiles when the corresponding shield is removed.

70 6. A steam-generating furnace comprising means forming a combustion chamber and including a water-wall across the top of said chamber, said wall comprising a series of spaced parallel water tubes extending across the top of the chamber, a header positioned at each end of said tubes and connected thereto, two rows of tiles between each adjacent pairs of tubes abutting at their sides and ends and enclosing substantially the entire length of said tubes, each tile having a longitudinally extending recess in one side thereof embracing the side, top and bottom of the adjacent tube, and a plurality of tube-protecting members movable downwardly onto the tubes to protect a part of the surface of said tubes and abut the tiles to prevent endwise displacement thereof, said members being of greater length than said tiles whereby to permit endwise withdrawal of the tiles when the abutting members are removed.

75 In testimony whereof we have hereunto affixed our signatures.
